(57) **CLAIM**

The ornamental design for a holding handle for terminal block, as shown and described.

DESCRIPTION

FIG. 1 is a perspective view of a holding handle for terminal block showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is second perspective view showing the holding handle for terminal block.

1 Claim, 8 Drawing Sheets
